PAPER CUTTER

Charles L. Hinsch, Piqua, Ohio

Application May 17, 1932, Serial No. 611,768

2 Claims. (Cl. 242—55.5)

53 This invention relates to new and useful improvements in paper cutters.

It is the principal object of this invention to provide for wrapping paper cutters, a guard having a fixed relation to the cutting blade, and rotatable inwardly therewith, to protect the fingers against injury when the blade is swung inwardly to expose a gripping edge of the paper to them.

In my construction the cutting edge of the 10 swinging blade is never exposed sufficiently to do injury to any one who is near it, being fully protected by the rotatable guard in its stationary position as well as when it is swung inwardly and outwardly just before a cutting operation.

15 Other important and incidental objects will be brought out in the following specification and particularly set forth in the subjoined claims.

In the accompanying drawing illustrating my invention, Figure 1 is a front view of one end of 20 my paper cutter, showing the rotatable cutting blade and guard therefor. Figure 2 is an end view of the same, partly in section, showing one of the swinging, supporting arms as a stamping for the gravity brake bar. Figure 3 is a similar 25 view, showing said arm as a casting. Figure 4 is a cross sectional view taken through the supporting arm illustrated in Figure 2, showing the tenoned end of the gravity brake bar projecting through the slot therein. Figure 5 is a perspective view, partly in section, of the rotatable guard 30 for the cutting blade. And Figure 6 is a perspective view, partly in section, of the swinging cutter-blade.

Referring to the accompanying drawing for a 35 detailed description of my invention, the numeral 1 designates a base upon which two standards 2 of a paper roll supporting frame are secured, one of said standards being shown in Figure 1. Mounted in bearing bosses 4 on the middle portions of said standards, are the ends of a shaft 5 40 for a roll of wrapping paper 6.

Pivots secured at its upper apertured end on a pin 7 projecting inwardly from the upper end of each standard 2 to complete the supporting 45 frame, is an arm 8, which in Figure 2 is shown as a stamping and in Figure 3 as a casting. Each arm 8 has a foot portion 9 directly above the heel of which an inclined slot 10 is formed to receive the flat, tenoned end 11 of a gravity brake bar 12. 50 In the casting 8 shown in Figure 3, an inclined recess 13 is formed to receive the tenoned end 11 of the brake bar.

Secured between the upper front end portions of the swinging arms 8, 8 is a rod 14. This rod 55 forms the pivotal support for a swinging or rotat-

able cutter blade 15 of the shape shown in Figure 6. Formed inwardly from the ends of this blade are ears 16, each one of which has a large aperture 17 and a small aperture 18. By means of their large apertures the ears 16 are fitted on the rod 14 so that they may pivotally depend from the latter to permit a swinging movement to the blade 15 within the limits defined by the gravity 60 brake bar 12 and the right-angled lugs 19, 19 formed on the outer ends of the arms 8, 8.

For the purpose of protecting a person against injury when imparting an inward movement to the cutter blade, or rubbing against it, I have provided a guard which consists of a U-shaped member 20. The upstanding ends 21, 21 of this 70 guard member are also formed with apertures 22 and 23 similar to those in the ears 16 on the blade 15. Through the large apertures 22 the ends 21 of the guard member are pivotally mounted on the rod 14, while the small apertures 23 register with the small apertures 18 in the blade ears 16 to receive rivets 24 by which the guard is firmly secured to the blade as shown in Figures 1, 2 and 3.

At its lower edge the blade 15 curves outwardly 80 and downwardly to a horizontal plane that is just far enough above the horizontal plane of the bottom of the guard member to permit the paper from the roll 6 to be easily drawn outwardly between the guard and the cutting edge of the blade 85 after said paper passes below the gravity brake bar 12. Immediately below the latter the paper from the roll 6 passes over a rod 25 which is secured at its ends to the standards 8, 8. (See 90 Figures 2 and 3).

The guard member 20 is bent downwardly along its rear edge to provide a right-angled finger piece 26 by which the guard and attached cutting blade may be pressed rearwardly to expose a sufficient amount of paper for a firm grip by the fingers so that the paper may be easily pulled out to a desired length and cut off after the blade has been returned to its normal vertical position by springs 27, 27.

These springs are coiled around the ends of the 100 fixed blade-supporting rod 14, with their outer ends bearing against the inner surface of the blade and their inner ends gradually contracted for a tight frictional grip upon the rod.

In operation, when it is desired to pull out a 105 desired length of paper to be cut from the roll 6, an inward finger pressure is first exerted against the guard member 20 through the depending finger piece 26. Unless the blade is moved inwardly, the edge of the paper, which lies flush 110

with the cutting edge of the blade, is difficult to grip. This rearward movement of the blade to expose a gripping edge of the paper, is accomplished with absolute safety, since the guard is connected to the blade to swing with it to the dotted line position shown in Figure 2 and thereafter return to its normal cutting position. The fixed relation of this guard member 20 to the blade at all times, protects from injury those who operate the cutter, or come near it when attending to other duties.

Having described my invention, I claim:

1. A paper cutter comprising a frame, a shaft journaled therein and supporting a roll of paper, a rod transversely mounted in said frame in front of said roll, a cutting blade having projecting ears pivotally mounted on said rod, whereby the blade has a swinging movement thereon, and a U-shaped member whose ends are secured to said

20

ears for a swinging movement with said blade, the bottom part of the U-shaped member being spaced from the cutting edge of the blade to form an opening through which the paper may be safely and easily drawn.

2. A paper cutter comprising a frame, a shaft journaled therein and supporting a roll of paper, a pair of spaced arms pivotally mounted at their inner ends in said frame, a cutting blade carried by the free ends of said arms, each arm having an enlarged portion behind its blade carrying part, the enlarged portions of said arms formed with oppositely disposed vertical slots, a transverse member fixed between the free ends of said arms below said slots, and a gravity brake bar vertically movable in said slots, to engage the paper over said transverse member.
